YARN-ADVANCING REEL

Arthur E. Guenther, Buffalo, N. Y., assignor to
 E. I. du Pont de Nemours & Company, Wilming-
 ton, Del., a corporation of Delaware

Application May 23, 1946, Serial No. 671,741

6 Claims. (Cl. 28—71.6)

1

This invention relates to a yarn-advancing apparatus, and more particularly to a yarn-advancing reel for continuously advancing yarn in the general form of a helix.

An object of this invention is to provide a new and improved yarn-advancing apparatus.

Another object of this invention is to provide a yarn-advancing reel in which a yarn is continuously advanced thereover in a general helical form.

Other and additional objects will become apparent hereinafter.

The objects of this invention are accomplished, in general, by winding a yarn in substantially helical form around a reel having a set of fixed yarn-carrying bars, arranged concentrically around and rotatable in a fixed circular path about the center axis of the reel axle, and a set of movable channel bars, positioned as hereinafter explained, which, during rotation thereof about the center axis of the reel axle, move radially (vary their distance from the center axis of the reel axle) and axially (oscillate longitudinally relative to the fixed bars).

The movable bars are located in the reel so that they will be moved in a circular path about the reel by driving contact of the fixed bars. In one embodiment, the movable bars are channel-shaped and a fixed bar is positioned in the channel of each of said movable bars.

The radial and axial movements of the movable bars are controlled by a pair of spaced eccentric discs which are so mounted in the reel that, upon rotation thereof about the reel axis, the discs will move in a perpendicular plane that is skewed with respect to a plane that is perpendicular to the axis of the axle. The movable bars are arranged circumferentially of the discs and are connected thereto by joints which permit the movable channel-shaped bars to have freedom of motion around the circumference of each of the skewed discs so that, during rotation of the reel, the yarn-contacting edges of such movable bars will move radially and axially and always be parallel to the center axis of the reel axle.

In one embodiment, the discs are rotatably mounted on eccentrics which are, in turn, mounted on the reel axle in a position which is skewed with respect to the center axis of the reel axle. The eccentric is of such design that during approximately one-half of a revolution of the reel, the movable bars project beyond the fixed bars into yarn-carrying position and move laterally in the direction of the feed of the yarn to advance the yarn across the reel. During approximately

2

the remaining half of the revolution, the movable bars are in retracted position below the fixed bars and move laterally in the direction opposite to that of the yarn travel for a distance equal to that travelled by the movable bars in yarn-advancing position. When the reel is viewed from the end, it will be observed that the movable bars travel in an elliptical path around the offset axis of the eccentrics.

- 10 In one embodiment of the invention, each channelled movable bar is formed of two blades secured in the desired spaced relationship by a spacer. Each of the movable channelled bars is provided with a pair of bearings, each of which respectively 15 cooperates with a cylindrical segment carried by the skewed disc. One of the bearings of each pair is self-positioning so that it can shift axially of the reel and prevent binding of the moving parts.
- 20 The movable channelled bars are located on the center line of the fixed bars and move radially and laterally thereof. To facilitate such movements, each of the fixed bars is provided adjacent each end thereof with guide discs formed 25 of a self-lubricating material.

The invention will be more clearly understood by reference to the following detailed description when taken in connection with the accompanying drawings, in which:

- 30 Figure 1 is a longitudinal section, with parts omitted for clarity, of a yarn-advancing reel of the present invention;
- Figure 2 is a section taken on the line 2—2 of Figure 1;
- 35 Figure 3 is a section taken on the line 3—3 of Figure 1;
- Figure 4 is a section taken on the line 4—4 of Figure 1;
- Figure 5 is a section taken on the line 5—5 of Figure 1;
- 40 Figure 6 is a section taken on the line 6—6 of Figure 1;
- Figure 7 is an elevation of one of the bearings of one of the universal joints;
- 45 Figure 8 is a front elevation of the adjustable bearings; and
- Figure 9 is a front elevation of the adjustable bearing guide.

Referring now to the drawings, wherein like reference numerals designate like parts, the reference numeral 10 designates a stationary axle of the reel, one end of which is fixedly secured by appropriate means in an outboard support 12. An end plate 14 is provided with a hub 16 which is 55 rotatably disposed on a concentric bushing 18

Secured on the axle 10. The hub 18 is secured to the end plate 14 by means of bolts 22 and spacer plate 24.

The end plate 14 is secured to a flange 28 of a casting 30 by means of bolts 32, which also cooperates with the spacer plate 24. The casting 30 is secured onto one end of a drive shaft 34, which is supported in an outboard bearing 36 and driven in any suitable manner by means not shown.

An end plate 40, disposed in spaced relationship with respect to end plate 14, is provided with a hub 42 which is secured thereto by means of bolts 44 and a spacer plate 46. The hub 42 is rotatably mounted on concentric bushing 52 mounted on the axle 10.

If desired, a plurality of spaced tie bars (not shown) can be secured to the end plates 14 and 40 in any convenient manner, it being understood that the tie rods will pass through holes (not shown) in the discs 128 and 148 so that there will be no interference between their relative motion.

A plurality of bars 54 are arranged equidistantly and in spaced relationship along the peripheries of both of the end plates 14 and 40 to which they are secured, as will now be described. Each of the bars 54 is provided at the opposite lower ends thereof with a plate 58 having a flange 60 and a plate 62 having a flange 64 respectively. Flange 60 is seated on end plate 14 and bolts 66 secure the plate 58 to the end plate 14. Flange 64 is seated on end plate 40 and bolts 68 secure the end plate 62 to the end plate 40. For reasons which will become apparent hereafter, each of the bars 54 is provided with an elongated slot 69 in the bottom edge thereof.

From the description thus far, it is apparent that upon rotation of shaft 34 the end plate 14 will be caused to rotate about the center axis of the axle 10. Since the bars 54 are rigidly secured to end plates 14 and 40, the rotary movement of the end plate 14 will be imparted to end plate 40 which will also rotate about the center axis of the axle 10. As a consequence, the bars 54 will be rotated in a fixed circular (concentric) path about the center axis of the axle 10. The bars 54, as will hereafter appear, are yarn-contacting bars and, since they are fixed, i. e. do not have any radial or axial movement, are hereinafter called "fixed yarn-supporting bars." In other words, the fixed yarn-supporting bars 54 and the end plates 14 and 40 constitute a rigid casing rotatable about the center axis of the axle 10.

As is shown in the drawings, each fixed yarn-supporting bar 54 is located in the channel of a channel-shaped yarn-contacting bar, which is generally designated by the reference numeral 70. Each channeled yarn-contacting bar 70 is formed of two blades 71 maintained in spaced relationship by a spacer 74 to which the blades are secured by means of bolts 76.

Each of the blades 71 is provided with a pair of slots 80 and 82 respectively. The slots 80 and 82, in one of the blades of a channel-shaped bar, are in alignment with corresponding slots in the other blade. As is shown in Figure 1, the slots 80 and 82 are so positioned in the blades that they are disposed adjacent the slot 69 in the fixed bar.

Between the slots 80 in each pair of blades 71 and extending transversely of the slot 69 in the fixed bar 54, there is a bearing 86 which is provided with a keyhole slot 88, the circular portion of which, as will hereafter appear, constitutes a bearing surface. Bolts 90, extending through holes 92 in the bearing 86 and aligned holes in the blades 71, secure the bearing in position.

The bearing 86, as shown in Figure 3, is of a thickness equal to the space between the blades 71 and also serves to maintain the blades in proper spaced relationship.

Between the slots 82 in each pair of blades 71 and extending transversely of the slot 69 in the fixed bar 54, there is a bearing 93 which, as shown in Figure 8, is provided with a keyhole slot 94, the circular portion of which, as will hereafter appear, constitutes a bearing surface. The bearing 93 is self-positioning and is arranged so that it can shift axially of the reel and thus prevent possible binding of the moving parts due to inaccuracies in machining or warping of parts due to temperature. As shown in Figure 5, the bearing 93 is disposed between a pair of positioning members 96. Each positioning member 96 is slotted, as indicated by the reference numeral 100 (see Figure 9), and on its inner surface is provided with tongues 102 which are disposed in grooves 104 in the bearing 93. Each positioning member is provided with holes 106 which are in alignment with slotted holes 108 in the bearing 93. A bushing 109 of a length slightly longer than the width of the bearing 93 is positioned in each slotted hole 108 between the members 96 and in alignment with the respective holes 106. A bolt 110 extends through each pair of aligned holes 106 and the bushing 109 therebetween. A nut 111 on each bolt 110 is drawn up tightly, clamping the assembly together. By this construction, the bearing 93 is free for some movement normal to the plane of Figure 5. The tongues 102 cooperating with the grooves 104 serve to keep the parts in the desired mutual relation and permit the small movement allowed to the bearing 93.

In each of the bearings 86 there is positioned a cylindrical segment 120, and in each of the bearings 93 there is positioned a similar cylindrical segment 122. Each cylindrical segment 120 is respectively secured, as by welding, to an arm 124 which is, in turn, secured by bolts 126 and plates 127 to a disc 128. The disc 128 has a central hub 130 secured to it by means of bolts 132 and rings 133 and 134. The hub 130 is rotatably mounted on an eccentric bushing 135 provided with a bore such that, when the bushing is disposed in position on the axle 10, it will be skewed with respect to the center axis of the axle 10.

Each cylindrical segment 122 is respectively secured to arms 144 which, in turn, are secured by bolts 146 and a plate 147 to a disc 148. The disc 148 has a central hub 150 secured thereto by means of bolts 152 and rings 153 and 154. The hub 150 is rotatably positioned on an eccentric bushing 155, the bore of which is such that when it is in position on the axle 10 it will be skewed with respect to the center axis of said axle. Eccentric bushings 135 and 155 are fixed on axle 10 and discs 128 and 148 are skewed so as to lie in parallel planes.

From the foregoing description, it is manifest that upon rotation of the fixed yarn-contacting bars 54, the movable channeled yarn-contacting bars 70 will be driven and rotated therewith. In order that the desired radial and axial movements be imparted to the movable bars 70 from the skewed eccentric discs 128 and 148, one of the channel-shaped bars, designated by the reference numeral 70' (see Figure 2), is secured to the discs 128 and 148. In the form shown (see Figure 2), each of the cylindrical segments 120 operating with the bearings 86 and 93 in the channel-shaped bars 70 is secured to the disc 148.

shaped bar 70' is secured by means of a bolt 160 to a pair of driving cups 162 positioned on each end of the cylindrical segment. Due to this construction, the channeled member 70' is secured to the discs 128 and 148 so that it does change its position during rotation of the reel in respect to discs 128 and 148 and upon rotation of the reel, rotary movement imparted to the channeled yarn-supporting bar 70' by the fixed bar in the channel thereof will be transmitted to the discs 128 and 148 whereby such discs will rotate about their respective skewed eccentrics 135 and 155 respectively and control the radial and axial movements of the channel bars 70. The assembly of the movable bars and the discs for controlling the radial and lateral movements thereof constitutes a non-rigid cage.

Due to the construction, as the discs are revolved on the skewed eccentric bushings, the channel bars will vary their distance from the center line of the axle 10 and also oscillate longitudinally with respect to the fixed bars.

The skewed eccentrics 135 and 155 are of such design that when the channeled yarn-supporting bars 70 are in the peripheral zone of the reel designated by the reference character A in Figure 2, the movable channel-shaped bars will be in yarn-contacting position and will move axially in the direction of the feed of the yarn across the reel. When the channel-shaped bars 70 are in the peripheral zone of the reel designated by the reference character B, they will be out of yarn-contacting position and moving in a direction opposite to the direction of yarn advancement over the reel. In the peripheral zones of the reel, designated by the reference characters C and D, the yarn is supported by both the fixed and movable bars.

The cylindrical segments 120 and 122 cooperating with the bearings in which they are respectively located constitute universal joints, which permit the movable channeled bars to have freedom of motion around the circumference of each of the skewed discs so that, during rotation of the reel, the yarn-contacting edges of the channeled bar will, irrespective of its radial and axial movement, always be parallel to the center axis of the reel axle.

The movable channeled yarn-contacting bars 70 are located about the fixed bars 54 so that they can move radially and laterally thereof. In order to facilitate such movement, the fixed bars 54 are provided with guides which cooperate with the inner sides of the blades 71. As shown in Figures 2 and 6, these guides consist of two pairs of shouldered discs 170, each pair being disposed in opposed relationship in a hole in the fixed bar 54 and secured in position by screws 172. As shown in Figure 6, the exterior surfaces of the discs 170 are in contact with the inner sides of the blades 71. In the form shown, the discs 170 are made of a self-lubricating material, such as, for example, Micarta, a phenol-formaldehyde resin.

In Figure 1, wherein like numbers refer to like parts, 156 designates a sleeve, 157 designates a holding ring, 158 designates a spacing sleeve and 159 a bushing sleeve. These parts may or may not be used as desired.

As is apparent from the foregoing description, the non-rigid cage is driven by the rigid cage. Due to the construction and arrangement of the parts of the reel, upon rotation of the rigid cage the fixed bars 54 thereof will be revolved in a fixed circular path about the center axis of the

axle 10. During such rotation, rotary movement will be imparted to the movable bars and such motion transmitted to the respective discs by the secured cylindrical segments whereby radial and axial movements are imparted to the movable channeled bars in accordance with the contour of the eccentric skewed bushings.

The increment of the yarn advancement or magnitude of the pitch of the advancing yarn is determined by the degree to which the discs are skewed.

Though in the embodiment hereinbefore described the eccentric skewed bushings 135 and 155 are of such a design that during approximately one-half of the revolution of the reel the yarn will be carried and advanced in the direction of the yarn feed by the channeled bars 70 and during approximately the remaining half of the revolution the channeled bars 70 will be out of contact with the yarn and the latter is carried by the fixed bars 54, it is to be understood that the invention is not restricted thereto. By appropriate design of the eccentric bushings 135 and 155, the movable channeled bars 70 can be made to carry and advance the yarn for more or less than one-half (180°) of the revolution of the reel and the fixed bars 54 carry the yarn for the remainder of the revolution of the reel. Furthermore, by appropriate design of the eccentric bushings 135 and 155, the fixed bars 54 and the movable channeled bars 70 can be made to alternately carry the yarn a plurality of times during a single revolution of the reel. In the latter embodiment, the portions of the revolutions of the reel wherein the movable bars carry the yarn can be equivalent to or greater or less than those wherein the fixed bars carry the yarn.

The reel can be used for continuously advancing yarn in the general form of a helix. The yarn can be processed as desired while on the reel. Thus, for example, if the yarn is made by the viscose process, the casting 30 may constitute a part of the frame of the spinning machine and the yarn may be washed, desulfured, bleached or dried during its passage across the reel. If desired, the yarn can be stretched, while still wet with coagulating bath liquor or under the influence of hot water, by making the fixed and movable yarn-contacting bars progressively deeper toward the yarn wind-off and making the helices larger at that end. Alternatively, the fixed and movable channeled bars may be made progressively smaller toward the yarn wind-off end to allow for shrinkage during appropriate treatment, such as desulfuring or drying.

Though the invention has been specifically described in connection with a reel which is supported at both ends, it is to be understood that it is not restricted thereto. The invention can be applied to reels of the cantilever type.

The invention provides a yarn-advancing reel wherein the yarn is continuously and effectively advanced in the general form of a helix.

Since it is obvious that many changes and modifications can be made in the above-described details without departing from the nature and spirit of the invention, it is to be understood that the invention is not to be limited thereto except as set forth in the appended claims.

I claim:

1. In a yarn-advancing reel, a reel axle, a set of spaced fixed yarn-contacting bars arranged concentrically about said reel axle, means to rotate said fixed yarn-contacting bars about the center axis of said axle, a set of movable channel-shaped

yarn-contacting bars, each of said fixed yarn-contacting bars being disposed in the channel of a channel-shaped yarn-contacting bar, a pair of spaced skewed eccentrically mounted discs on said axle and carrying said channel-shaped yarn-contacting bars, means to secure one of said channel-shaped yarn-contacting bars in driving relationship with said discs, and a joint between each of the remaining channel-shaped yarn-contacting bars and said discs whereby radial and axial movements are imparted to each of said remaining channel-shaped yarn-contacting bars and such channel-shaped bars are maintained parallel to the center axis of said axle during rotation of the reel.

2. In a yarn-advancing reel, a reel axle, a set of spaced fixed yarn-contacting bars arranged concentrically about said reel axle, means to rotate said fixed yarn-contacting bars about the center axis of said axle, a set of movable channel-shaped yarn-contacting bars, each of said fixed yarn-contacting bars being disposed in the channel of a channel-shaped yarn-contacting bar, a pair of spaced skewed eccentrics mounted on said axle, a disc rotatably mounted on each of said skewed eccentrics and carrying said channel-shaped yarn-contacting bars, means to secure one of said channel-shaped yarn-contacting bars in driving relationship with said discs, and a joint between each of the remaining channel-shaped yarn-contacting bars and said discs whereby radial and axial movements are imparted to each of said remaining channel-shaped bars and such bars are maintained parallel to the center axis of said axle during rotation of the reel.

3. In a yarn-advancing reel, a reel axle, a set of spaced fixed yarn-contacting bars arranged concentrically about said reel axle, means to rotate said fixed yarn-contacting bars about the center axis of said axle, a set of movable channel-shaped yarn-contacting bars, each of said fixed yarn-contacting bars being disposed in the channel of a channel-shaped yarn-contacting bar, a pair of spaced skewed eccentrically mounted discs on said axle and carrying said channel-shaped yarn-contacting bars, means to secure one of said channel-shaped yarn-contacting bars in driving relationship with said discs, a plurality of cylindrical segments arranged circumferentially of and carried by each of said discs, and a pair of bearings at the bottom of each of the remaining channel-shaped members, one of said bearings cooperating with the cylindrical segment on one disc and the other of said bearings cooperating with the cylindrical segment on the other disc, whereby each of said remaining channel-shaped bars is moved radially and axially and always maintained parallel to the center axis of the axle during rotation of the reel.

4. In a yarn-advancing reel, a reel axle, a set of spaced fixed yarn-contacting bars arranged concentrically about said reel axle, means to rotate said fixed yarn-contacting bars about the center axis of said axle, a set of movable channel-shaped yarn-contacting bars, each of said fixed yarn-contacting bars being disposed in the channel of a movable channel-shaped yarn-contacting bar, a pair of spaced skewed eccentric bushings mounted on said axle, a disc rotatably mounted on each of said skewed eccentric bushings and carrying said channel-shaped yarn-contacting bars, means to secure one of said channel-shaped yarn-contacting bars in driving relationship with said discs, a plurality of cylindrical segments arranged circumferentially of

and carried by each of said discs, and a pair of bearings at the bottom of each of the remaining channel-shaped members, one of said bearings cooperating with the cylindrical segment on one disc and the other of said bearings cooperating with the cylindrical segment on the other disc, whereby each of said remaining channel-shaped bars is moved radially and axially and always maintained parallel to the center axis of the axle during rotation of the reel.

5. In a yarn-advancing reel, a reel axle, a set of spaced fixed yarn-contacting bars arranged concentrically about said reel axle, means to rotate said fixed yarn-contacting bars about the center axis of said axle, a set of movable channel-shaped yarn-contacting bars, each of said fixed yarn-contacting bars being disposed in the channel of a channel-shaped yarn-contacting bar, a pair of spaced skewed eccentrically mounted discs on said axle and carrying said channel-shaped yarn-contacting bars, means to secure one of said channel-shaped yarn-contacting bars in driving relationship with said discs, a plurality of cylindrical segments arranged circumferentially of and carried by each of said discs, and a pair of bearings at the bottom of each of the remaining channel-shaped members, one of said bearings cooperating with the cylindrical segment on one disc and the other of said bearings cooperating with the cylindrical segment on the other disc, whereby each of said remaining channel-shaped bars is moved radially and axially and always maintained parallel to the center axis of the axle during rotation of the reel, one of said bearings being self-positioning.

6. In a yarn-advancing reel, a reel axle, a set of spaced fixed yarn-contacting bars arranged concentrically about said reel axle, means to rotate said fixed yarn-contacting bars about the center axis of said axle, a set of movable channel-shaped yarn-contacting bars, each of said fixed yarn-contacting bars being disposed in the channel of a movable channel-shaped yarn-contacting bar, a pair of spaced skewed eccentrics mounted on said axle, a disc rotatably mounted on each of said skewed eccentrics and carrying said channel-shaped yarn-contacting bars, means to secure one of said channel-shaped yarn-contacting bars in driving relationship with said discs, a plurality of cylindrical segments arranged circumferentially of and carried by each of said discs, and a pair of bearings at the bottom of each of the remaining channel-shaped members, one of said bearings cooperating with the cylindrical segment on one disc and the other of said bearings cooperating with the cylindrical segment on the other disc, whereby each of said remaining channel-shaped bars is moved radially and axially and always maintained parallel to the center axis of the axle during rotation of the reel, one of said bearings being self-positioning.
